(57) **CLAIM**

The ornamental design of a press head for a hydraulic press tool, as shown and described.

DESCRIPTION

FIG. 1 is a perspective view of a press head for a hydraulic press tool;

FIG. 2 is a right side elevation view of the press head;

FIG. 3 is a front elevation view of the press head;

FIG. 4 is a left side elevation view of the press head;

FIG. 5 is a rear elevation view of the press head;

FIG. 6 is a top plan view of the press head;

FIG. 7 is a bottom plan view of the press head; and,

FIG. 8 is a cross-sectional view of the press head along line 8-8 of FIG. 6.

The elements shown in broken line in the drawings is for the purpose of showing environmental structure and forms no part of the claimed design.

1 Claim, 8 Drawing Sheets
